PERMUTATION PADLOCK

Harry E. Soref and James Keith Marshall, Milwaukee, Wis., assignors to Master Lock Company, Milwaukee, Wis., a corporation of Wisconsin

Application February 4, 1937, Serial No. 123,998

9 Claims. (Cl. 70—25)

The invention relates to locks and more particularly to permutation padlocks.

An object of the invention is to provide an improved and simplified permutation padlock 5 wherein the shackle is automatically locked upon its entry into the lock case.

Another object of the invention is to provide a padlock in which the tumbler permutation is automatically upset or disarranged upon the 10 entry of the shackle into the lock case.

A further object is to provide a padlock which is reliable in operation and is capable of economical manufacture.

The invention further consists in the several 15 features hereinafter described and claimed.

One specific embodiment of the invention is shown in the accompanying drawing, wherein

Fig. 1 is a rear view of a permutation padlock constructed in accordance with the invention, 20 parts being removed and broken away and parts being shown in section, the padlock being shown in locked condition;

Fig. 2 is a sectional view of the padlock taken generally along the line 2—2 of Fig. 1;

Fig. 3 is a view similar to Fig. 1, but with additional parts broken away and shown in section, the lock being shown in readiness for withdrawal 25 of the shackle;

Fig. 4 is a sectional view taken generally along 30 the line 4—4 of Fig. 1;

Fig. 5 is a view generally similar to Fig. 1, but showing the shackle fully withdrawn;

Fig. 6 is a view similar to Fig. 5, but showing the shackle entered into the lock to locking position;

Fig. 7 is a perspective view of a tumbler-rotating member;

Fig. 8 is a detail perspective view of a latch plunger forming a part of the lock, and

Fig. 9 is a detail perspective view of a shackle 40 guide and stop.

In the drawing, 15 designates a lock case of any suitable shape, and in the present instance of cylindrical form and comprising a front plate 45 16 and an embossed rear plate 17, the former plate being integral with the cylindrical portion of the case. The case has an enclosing cup-shaped shell 18, preferably a sheet metal stamping, which fits closely on the case and has a front 50 cover plate 19 engaging the front plate 16 of the case. An embossed rear cover plate 20 marginally bears on the rear plate 17, and both of these plates are secured in place by a flange 21 formed by spinning over the rear edge of the shell 18. 55 Preferably, the front and rear plates 16 and 17

are further secured in place by riveted pins or posts 22 and 23, which also secure the front cover plate 19 of the shell to the front plate 16 of the case.

A guide member 25, preferably in the form of a sheet metal stamping, is rigidly secured within the case, and comprises a flat portion 26 which rests on the inner face of the front plate 16 and is secured thereto by the riveted pin 23. Struck up from an end of the flat portion 26 of the member 10 25 is a flange 27 which extends between the front and rear plates 16 and 17 and is provided with opposite lugs 28 which fit in anchor slots 29 formed in these plates. A round shackle-guiding opening 30 is formed in the flange 27. 15

A U-shaped shackle 31 has its legs slidably passing through openings 32 formed in the case and shell. The longer leg of the shackle also slidably and rotatably passes through the opening 30 in the guide member 25, and the shorter 20 leg has a beveled end 33 and a locking notch 34 near this end. When the shackle is withdrawn to its outermost position, the shorter leg clears the shell 18, as seen in Fig. 5, and the shackle is then capable of being swung about its longer 25 leg. The longer leg of the shackle is provided with a keyway 35 in which slidably fits a guide tongue 36 struck up from the guide member 25. An annular groove 38 is formed about the end portion of the longer shackle leg and slidably receives therein a forked guide and stop plate 39 which is confined on the shackle leg by the 30 slidable engagement of a straight edge of the plate with the flat inner surface of the case plate 17, this engagement also guiding the shackle leg and preventing rotation of the forked plate with respect to the case. The forked plate is engageable with the flange 27 of the guide member 25 to limit the outward movement of the shackle, as seen in Fig. 5. When the shackle is in its outer 35 or withdrawn position, it clears the tongue 36 to permit free swinging of the shackle.

A locking lever 41, forming a locking member, is pivotally mounted on the pin 22 and movably carries a spring-pressed latch member, here shown 45 to be in the form of a cylindrical latch plunger 42 slidably in a bore 43 formed in the locking lever at right-angles to the pin 22. The latch plunger has a beveled nose 44 engageable in the shackle notch 34 to resist withdrawal of the 50 shackle when the locking lever is locked, as hereinafter described. A compressed coiled spring 45 within the locking lever extends within the hollow inner end of the latch plunger and urges the latch plunger outwardly. A flat-bottomed 55

notch or recess 46 in one side of the latch plunger receives the pin 22 which thus forms a stop limiting the outward movement of the latch plunger and also prevents relative rotation of the 5 plunger with respect to the locking lever. An arcuate tongue or lip 47 on the locking lever cooperates with tumbler means hereinafter described.

A stud 48 is rigidly secured, as by riveting, to 10 an embossed portion of the rear case plate 17 and projects forwardly through apertured portions of the front plate 16 and front cover plate 19. The tapered front end of the stud 48 loosely fits in a bore 49 formed in an operating knob 15 50 which is rotatably mounted in the front plate 16. A dished dial plate 51 is carried on the knob against relative rotation, the knob having at its inner end a cross slot 53 forming a keyway. The rim of the dial is surrounded by an annular bead 20 54, Fig. 2, which is embossed on the front cover plate 19 of the padlock shell. The dial plate bears the usual indicia, not shown, and conceals the riveted front ends of the pins 22 and 23.

A driving tumbler or disk 55 is concentric and 25 rigid with the knob 50, as by riveting it on the slotted end of the knob, and carries the usual transfer lug 56. One or more additional tumblers or disks 57 and 58 are rotatable on the stud 48 and carry transfer lugs 60. The tumblers are 30 separated by washers 61 which have key projections entering a keyway 62 on the stud 48 and are placed under friction by a compressed coil spring 63 surrounding the rear portion of the stud 48. As seen in Fig. 2, the keyway 62 35 stops short of the front end of the stud so as to retain the tumblers 57 and 58 and other parts on the stud prior to the attachment to the case of the stud-carrying rear plate 17, which thus forms an easily handled sub-assembly.

40 The tumblers 55, 57 and 58 have peripheral slots or notches 64 formed therein to admit the tongue 47 of the locking lever when these slots are registered by adjusting the knob 50, thus permitting the locking lever to be swung to permit 45 the release of the shackle 31. The locking lever has a flat surface 67, Fig. 3, engageable with the peripheries of the tumblers to limit rotation of this lever in one direction during closing of the shackle.

50 The tumbler 58 is provided with a pin or projection 66 at its rear side engageable by a downwardly projecting arm of a plate-like lever 68 which is pivotally mounted on the pin 22, the lever having a bore 69 to receive the pin. A 55 side of the locking lever 41 is cut away to receive the lever 68 and to form a shoulder or abutment 70 engageable with the upper edge of the lever 68, this upper edge being cut away at 71 to permit a small relative angular movement between 60 these two levers. The lever 68 is confined between the locking lever 41 and the case plate 17. One side edge 72 of the downwardly projecting arm of the lever 68 has a concave form to permit rotation of the rearmost tumbler, which 65 carries the projection 66. The lever 68 has a forwardly projecting arm 73 which is engageable by the lower end of the short shackle leg to swing the lever, as hereinafter described.

When the padlock is to be opened, the combination knob 50 is turned alternately in opposite directions to successive predetermined positions, thus rotating the tumblers to bring the notches thereof in registered position for admitting the tongue 47 of the locking lever 41. Fig. 3 shows 75 the lock after the tumblers have been thus ad-

justed. During the rotation of the tumbler 58, the projection 66 thereof will displace the lever 68 slightly on its pivotal axis so that the tumbler is free to turn one or more revolutions in either direction, the projection sliding along the concave cam-forming edge 72 of the downwardly projecting arm of the lever. After the tumbler notches are brought into register, the shackle is displaced outwardly with respect to the lock case, as seen in Fig. 5, the locking lever 41 being tilted 10 by the notched end of the withdrawing shackle, and the lever 68 being tilted with the locking lever. The outward movement of the shackle is limited by the engagement of the forked plate 39 on the shackle with the flange 27 of the guide 15 member 25. In its outermost position the longer leg of the shackle clears the guide tongue 36 of the guide member 25, thereby permitting the shackle to be swung in either direction about its longer leg. When the shackle is thus angularly 20 displaced in either direction it can not be moved longitudinally, since the guide tongue 36 is out of register with the keyway 36 in the shackle, thus facilitating manipulation of the padlock.

When the padlock is to be locked, the shorter 25 leg of the shackle is re-entered into the case, the beveled end of the shackle leg engaging the arm 73 of the lever 68, thus moving the lever 68 downwardly. The lever 68, being at its upper edge engageable with the shoulder 70 of the locking lever 41, swings the locking lever to its normal position, the latch plunger 42 entering the notch 34 of the shackle leg. The lower end of the lever 68 engages the projection 66 of the tumbler 58, as seen in Fig. 6, thus turning this 30 tumbler, and in some instances one or both of the tumblers 57 and 55, out of unlocking position, and disarranging the permutation. In the tumbler-turning or upsetting operation, the shackle is moved inwardly on its locking movement a short distance past its normal locking position, as seen in Fig. 6.

When the shackle is withdrawn, frictional engagement will hold the levers 41 and 68 in the angularly displaced positions seen in Fig. 5. In 45 this condition of the lock the shackle may be returned to its locked position without requiring any yielding of the latch plunger 42. If, however, after the shackle is withdrawn, the lever 41 should be permitted to return to or near its 50 normal or locking position the re-entry of the shackle would then cause the latch plunger 42 to yield against the action of its spring 45. The latch plunger spring will be required to operate only infrequently, if at all.

55 The construction of the padlock is such as to require relatively few parts and to simplify assembly. For example, the pin 22 connects the front and rear plate of the case, secures the front cover plate of the shell to the front plate 60 of the case, forms a pivot for both the locking lever and combination-upsetting lever, forms a stop for the latch plunger, and prevents rotation of the latch plunger. The forked plate 39 on the shackle forms both a shackle stop and guide 65 and avoids the necessity for riveting or upsetting operations on the shackle after it is inserted in the lock case.

What we claim as new and desire to secure by Letters Patent is:

70 1. In a permutation padlock, the combination of a shackle, shackle-locking means including a rotatable tumbler movable to release said shackle, and a shiftably mounted member directly engageable with said tumbler and shackle and disposed 75

in the path of movement of a portion of said shackle to rotate said tumbler out of unlocking position upon the locking movement of said shackle.

5 2. In a permutation padlock, the combination of a shackle, shackle-locking means including a rotatable tumbler movable to release said shackle, and a pivotally mounted member directly engageable with said tumbler and shackle and disposed in the path of movement of a portion of said shackle to rotate said tumbler out of unlocking position upon the locking movement of said shackle.

10 3. In a permutation padlock, the combination of a shackle, shackle-locking means including a movable shackle-locking member and a rotatable tumbler movable to release said member out of locking position, and a shiftably mounted member engageable with said tumbler and with said movable shackle-locking member and disposed in the path of movement of a portion of said shackle to move said shackle-locking member to locking position and to rotate said tumbler out of unlocking position upon the locking movement of said shackle.

15 4. In a permutation padlock, the combination of a shackle, shackle-locking means including a pivotally mounted shackle-locking member and a rotatable tumbler movable to release said member out of locking position, and a lever coaxial with said shackle-locking member and engageable with said shackle and said tumbler to rotate said tumbler out of unlocking position upon the movement of said shackle.

20 5. In a permutation padlock, the combination of a shackle, shackle-locking means including a pivotally mounted shackle-locking member and a rotatable tumbler movable to release said member out of locking position, and a lever coaxial with said shackle-locking member and engageable with said shackle and said tumbler to rotate said tumbler out of unlocking position upon the movement of said shackle, said shackle-locking member and lever being coupled together but

capable of a limited relative angular movement.

25 6. In a permutation lock, the combination of a locking means including a movable locking member, a rotatable tumbler for blocking the unlocking movement of said locking member and movable out of blocking position, a lockable member engageable with said locking means, and a pivotally mounted member directly engageable with said tumbler and lockable member and disposed in the path of movement of a portion of said lockable member to rotate said tumbler out of unlocking position upon the locking movement of said lockable member.

10 7. In a permutation lock, the combination of a lockable member, locking means including a rotatable tumbler movable to release said lockable member, and a shiftably mounted member directly engageable with said tumbler and lockable member and disposed in the path of movement of a portion of said lockable member to 15 rotate said tumbler out of unlocking position upon the locking movement of said shackle.

20 8. In a permutation lock, the combination of a lockable member, locking means including a movable locking member and a rotatable tumbler movable to release said member out of locking position, and a shiftably mounted member directly engageable with said tumbler and said locking member and said lockable member to move said locking member to locking position and to rotate 25 said tumbler out of unlocking position upon the locking movement of said lockable member.

25 9. In a permutation padlock, the combination of a shackle, shackle-locking means including a pivotally mounted shackle-locking member and a rotatable tumbler movable to release said member out of locking position, and a lever coupled with said shackle-locking member and engageable with said shackle and said tumbler to move said member to shackle-locking position and to 30 rotate said tumbler out of unlocking position upon the movement of said shackle.
